Attorney, Agent, or Firm—Fisher, Christen & Sabol

[57] **CLAIM**

The ornamental design for a spout, as shown and described.

DESCRIPTION

FIG. 1 is a perspective view taken from the top, front and left side of a spout showing my new design; FIG. 2 is a left side elevational view thereof, the right side being a mirror image of the left side shown; FIG. 3 is a front elevational view thereof; FIG. 4 is a rear elevational view thereof; FIG. 5 is a perspective view taken from the top, front and left side of a modified form of the spout shown in FIG. 1;

FIG. 6 is a left side elevational view of FIG. 5, the right side being a mirror image of the left side shown; FIG. 7 is a front elevational view of FIG. 5;

FIG. 8 is a rear elevational view of FIG. 5; FIG. 9 is a perspective view taken from the top, front and left side of a second modified form of the spout shown in FIG. 1;

FIG. 10 is a left side elevational view of FIG. 9, the right side being a mirror image of the left side shown; FIG. 11 is a front elevational view of FIG. 9; and FIG. 12 is a rear elevational view of FIG. 9.
